ANDREW McILWRATH, OF CHICAGO, ILLINOIS, ASSIGNOR TO FLOOD & CONKLIN CO.,
OF NEWARK, NEW JERSEY, A CORPORATION OF NEW JERSEY.

WOOD-VENEERING.

1,092,846.

Specification of Letters Patent. Patented Apr. 14, 1914.

Application filed November 11, 1912. Serial No. 730,599.

To all whom it may concern:

Be it known that I, ANDREW McILWRATH, a citizen of the United States, and a resident of Chicago, county of Cook, and State 5 of Illinois, have invented a certain new and useful Improvement in Wood-Veneering, of which the following is a specification.

My invention relates to the veneering of wood and particularly to the treating and 10 building up of veneered wood in such manner that a permanent and satisfactory finish may be given thereto, which will not be subject to checking, peeling, shrinking in, or other action having the tendency or effect of 15 preventing the satisfactory application of a proper finish or of marring or destroying the finish after its completion.

For numerous reasons, including the scarcity and expensiveness of woods suitable 20 for forming the exterior surfaces of pianos, the better class of furniture and the like products of wood, veneers are made extremely thin, the customary practice with many kinds of wood being to make veneers 25 thereof as thin as three to four one-hundredths of an inch in thickness. In all thin veneers there are very numerous small openings, many of which are large enough to permit the passage of light and to be readily 30 visible to the naked eye when held up before a source of light. By reason of the numerous openings in the thin veneer and the pressure used in gluing the veneer to its backing, glue when applied directly to the 35 veneer or backing penetrates through the veneer and appears over practically the entire area of the veneer upon its outer surface or face so that the surface thus formed is made up very largely of the glue used for 40 securing the veneer to the backing piece. When finishing materials such as stains, fillers, lacquers, varnishes and the like are applied to this wood-glue surface, it is impossible to obtain a permanent and satisfactory 45 finish, for, by reason of the presence of glue on the surface where it comes into contact with the finishing materials, the finished surface is subject to the effects of moisture, changes of temperature and similar causes, and checking, peeling, shrinking in, and other harmful actions manifest 50 themselves and prevent the obtaining and maintaining of the necessary high finish.

According to my invention the veneer is

subjected to treatment, prior to the gluing 55 operation, with a material of kindred nature to the finishes ultimately to be applied to the veneered wood and which will penetrate and partially or wholly fill the pores and openings in the veneer so as to prevent the glue 60 from penetrating and coming through the veneer, and which at the same time will have the effect of making the veneer substantially moisture and temperature proof. When the veneer is so treated and the glue is prevented 65 from coming into contact with the finishing materials, they readily and permanently adhere thereto and the finished surface is not subject to the checking, peeling, shrinking in and the like tendencies found when the 70 finishing materials are applied to the wood-glue surfaces heretofore formed. I preferably make use for treating the veneer for this purpose of a gum solution such as a solution of refined shellac, sandarac, damar, 75 mastic or fossil gums, all of which may be used either in combination or separately, and which have the capacity of excluding the glue from the pores and openings in the veneer and are capable of taking and holding a 80 high finish. The veneer may be treated with such materials on one or both sides and its treatment with said materials may be carried out in any manner which will secure the result of filling the pores and openings in the 85 veneer with the material sufficiently to prevent the glue from coming through the veneer, as, for example, the gum solution may be applied to the veneer by means of a brush, or by a roll or rolls, or the veneer may be 90 dipped into a bath of the material or other methods of treatment may be resorted to for this purpose. After such treatment, the veneer which has been treated is thoroughly dried and is preferably subjected to pressure 95 during the drying process so as to prevent distortion and malformation, and the veneer so treated and having the pores and openings therein sufficiently filled with a hardened gum solution to prevent the glue from going 100 through to the surface of the veneer is glued to its backing in the ordinary manner. The glue, however, after the veneer has been treated in the manner described, does not penetrate through the veneer but is confined 105 to its legitimate function of securing the veneer to its backing, and after the gluing process is completed, the outer surface or

face of the composite piece so formed is substantially free from glue and is made up of the veneer wood and of the hardened gum solution, and it comprises, so to speak, a 5 wood-gum surface, instead of a wood-glue surface as when the glue is applied to the bare veneer. This surface partakes very largely of the characteristics of the hardened gum solution with which the veneer 10 has been treated and the surface so formed is not affected by moisture or by considerable changes in temperature. I have found that the stains, fillers, lacquers, varnishes and the like used for finishing purposes being of a 15 kindred character to the gum solution adhere very strongly to this surface and that after the surface has been finished by the application thereof there is no manifestation of the peeling, shrinking in, checking or 20 other troublesome defects to which finishes applied on ordinary veneered wood are subject.

When the gum solution is applied only to the back of the veneer, as may be done if 25 desired, the amount of the hardened gum solution appearing on the outer surface will be very much less than if the veneer is dipped into the solution or otherwise treated on both surfaces, but in any case the glue 30 is excluded from the outer surface where it would come into contact with the materials used in finishing when they are applied in the liquid state and the harmful results due to such contact are prevented.

35 With the foregoing and related objects in view, my invention consists of the parts, improvements, combinations and processes herein set forth and claimed.

While I illustrate and describe particular 40 embodiments of my invention, it is to be understood that my invention is not limited thereto but is as broad as my claims.

In the drawings forming part of this specification, the single figure represents in 45 cross section a built up piece of wood in accordance with the invention.

In the said drawing reference numeral 1 is applied to the backing piece or core which may be of any kind of inexpensive wood 50 usually made use of for that purpose; 2 represents a section of cross-grained wood secured thereto by means of the glue 3 and having the grain at right angles to the backing piece or core 1, and which is customarily 55 interposed between the backing piece and the surface veneer, but it is not essential for the practice of my invention and may be dispensed with if desired.

Reference numeral 4 represents the 60 surface veneer and 5 the material with which the pores and openings in the veneer 4 are

filled, and 6 represents the glue which is used for securing the veneer 4 in place.

As the backing piece or core 1 and the cross-grained piece 2 are not treated to prevent the penetration thereof by the glue, it penetrates therein to a considerable depth, while its penetration into the veneer 4, which has previously been treated with the gum solution is relatively inconsiderable. 70

The manner of treating the veneer and of securing it in place upon the backing is in all respects as heretofore described, the veneer 4 being first treated with gum solution 5, then dried and glued in place, the material 5 acting to prevent the glue 6 from penetrating to the outer surface of the veneer where it would come into contact with the materials used in finishing, and the glue 6 being confined to its proper function of 80 securing the veneer in place on its backing, and being substantially excluded from the outer surface 7 of the veneer 4, so that the finishing materials may be applied to a surface free from glue, and already having a 85 surface made up at least in part of materials to which the finishing materials will readily and permanently adhere.

Having now described my invention, I 90 claim:

1. That improvement in the art of wood veneering which consists in treating the veneer with a gum solution and causing the material to harden so as to substantially exclude glue from the pores thereof, and 95 gluing the veneer so treated to the backing, substantially as set forth.

2. In combination, a backing of wood, a veneer having a hardened gum solution in the pores and openings therein and being 100 secured to the backing by means of glue, the glue being excluded from the outer surface of the veneer by reason of the presence of the hardened gum solution, substantially as set forth. 105

3. In combination, a backing piece, a section of wood glued thereto and having its grain crossing that of the backing piece, and a veneer having its grain parallel to that of the backing piece, and glued to the cross-grained section and having a gum solution in the pores and openings therein, substantially 110 as set forth.

In testimony whereof I have signed my name hereto in the presence of two subscribers witnesses this 8th day of November, 115 1912.

ANDREW McILWRATH.
